(57) **CLAIM**

The ornamental design for a case for electronic device, as shown and described.

DESCRIPTION

FIG. 1 is a first perspective view of a case for electronic device showing our new design;

FIG. 2 is a first rear view thereof;

FIG. 3 is a front view thereof;

FIG. 4 is a view of the first side thereof;

FIG. 5 is a view of the second side thereof;

FIG. 6 is a first top view thereof;

FIG. 7 is a bottom view thereof;

FIG. 8 is a second perspective view thereof, wherein the portion of the case for electronic device comprising the claimed design is shown separated from an environmental portion of the case for electronic device;

FIG. 9 is a second rear view thereof in which the case for electronic device is shown in a first alternate configuration;

FIG. 10 is a third rear view thereof in which the case for electronic device is shown in a second alternate configuration;

FIG. 11 is a fourth rear view thereof in which the case for electronic device is shown a third alternate configuration;

FIG. 12 is a second top view thereof in which the case for electronic device is shown in the first alternate configuration;

FIG. 13 is a third top view thereof in which the case for electronic device is shown in the second alternate configuration; and,

FIG. 14 is a fourth top view thereof in which the case for electronic device is shown in the third alternate configuration.

The broken lines in the drawing figures form no part of the claimed design and depict portions of the case for electronic device that form no part of the claimed design.
